United States Patent Office

Des. 197,786
Patented Mar. 24, 1964

197,786

SAVINGS BANK

Don C. Pierce, Jr., 115 Moore St., Bellevue, Ohio

Filed July 10, 1963, Ser. No. 75,729

Term of patent 14 years

(Cl. D34—11)

FIG. 1

FIG. 2

FIG. 3

FIG. 4

I claim:
The ornamental design for a savings bank, substantially as shown.
